UNITED STATES PATENT OFFICE.

PHILLIPP DRINKAUS, JR., OF DETROIT, MICHIGAN.

ROTARY STAMPING-MACHINE.

SPECIFICATION forming part of Letters Patent No. 283,871, dated August 28, 1883.

Application filed January 31, 1883. (No model.)

To all whom it may concern:

Be it known that I, PHILLIPP DRINKAUS, Jr., of Detroit, in the county of Wayne and State of Michigan, have invented new and useful 5 Improvements in Rotary Stamping-Machines; and I do hereby declare that the following is a full, clear, and exact description thereof, reference being had to the accompanying drawings, which form a part of this specification. 10 This invention relates to machines for manufacturing ornamental composition strips, which are employed as ornamentation to the fronts of picture-frames, by means of which such strips can be manufactured in indefinite 15 lengths.

The composition ornamentations applied to the fronts of frames have hitherto been made by working the composition into lengths of about twelve inches and then stamping the 20 face side of such composition with the pattern desired. This is a slow and tedious process, and one which requires the adjacent ends of the various strips to be matched in laying the same upon the frame, and it frequently also 25 happens that the depth of the imprint of the ornamentation-pattern so varies as to create an unpleasant appearance to the eye when the frame is finished.

It is the object of the present invention to 30 provide a machine by means of which perfect work will be done, the imprinting or stamping of the ornamentation being uniform upon a strip, which may be continued to an indefinite number of feet in length.

35 The invention consists in the peculiar construction of the parts of the machine and their combination and operation, as more fully hereinafter described.

Figure 1 is a perspective view of my machine. Fig. 2 is a detached elevation of the ornamentation-roll, the view being taken from the front thereof.

In the accompanying drawings, which form a part of this specification, A represents a bed, 40 upon which are journaled two drums, B, which carry an endless belt, C, upon which the composition is placed to feed the machine. Another pair of drums, D, carry another endless belt, E, which carries off the finished ornamental strip as it passes from the machine. F 45 is a smooth-faced iron roll, suitably journaled

at each end to the frame, and G are suitable standards or brackets rising from the top of said frame, and to these brackets, by means of boxes H, which are vertically adjustable by 55 means of set-screws I, is journaled the ornamentation-roll J. The drums B D and roll F are upon the same plane, and may be driven from any suitable source of power. The ornamentation-wheel J or stamp is made of wood, 60 preferably of maple, box-wood, or apple, or of other wood suitable for engraving purposes, and is so made as to present the end of the wood at the periphery of the wheel, and upon these any particular pattern of ornamentation 65 may be cut, in relief or in intaglio. Upon each side of this ornamentation-wheel there are secured to the shaft disk-cutters R, which project beyond the face of the wheel itself by just so much as the thickness of the composition or the strip, so that as the latter is fed in from the endless belt C by the rotation of the roll F and wheel J, it is drawn between them, receiving the impress of the wheel upon 70 its face side, while at the same time the disk-cutters trim the edges parallel with each other. The shaft upon which the wheel J is secured may be so journaled as to be readily removed for the purpose of substituting any other pattern of ornamentation-wheel; and to this end 75 80 one or both the disk-cutters may be so secured to the shaft as to readily be removed.

By means of a device constructed and operating substantially as above described I am enabled to turn out this particular style of 85 work with great rapidity, very uniform and even, and at but a moiety of the expense attending its manufacture as ordinarily done.

It will be observed that as there is a space left upon each side of the roll F, and between 90 it and the drums B D, the composition fed upon the apron C would fall into one of these spaces. In order to prevent this, I use upon each side of the roll F a bridge, S, (shown detached in Fig. 1 and in dotted lines upon the same figure,) the top of this bridge being at or about 95 the same plane as the top of the drums B D and roll F, so that the composition strip will pass over this bridge from the carrier-belt to the roll. Upon this bridge I secure so as to 100 be laterally adjustable, by means of a bolt and slots, the plates T, to which are journaled the

vertical guide-rolls U. The object of making these feed-roll carrying-plates T adjustable laterally, as shown, is to accommodate them to various widths of strips to be stamped.

5 What I claim as my invention is—

1. In a rotary stamping-machine for the purposes described, the combination, with the rolls B B and D D, the endless aprons C and E, and the transverse roll F, of the vertically-adjustable molding-roll J, having adjustable cutters R, as and for the purposes set forth.
- 10

2. In combination with the apron E, roll F, molding-roll J, having adjustable cutters R, adapted to support the formed strip, and the adjustable plates T, having vertical rollers U, 15 to guide the formed strip and finish the edges, as set forth.

PHILLIPP DRINKAUS, JR.
